UNITED STATES PATENT OFFICE.

ALICE B. HOLT, OF GRAFTON, WEST VIRGINIA.

CLAMP ATTACHMENT FOR BEDS.

Application filed May 11, 1926. Serial No. 108,315.

My invention relates to improvements in clamp attachments for beds, and it consists in the combinations, constructions and arrangements herein described and claimed.

5 An object of the invention is the provision of an attachment for beds which affords facilities for holding bed clothing or covering smoothly and closely against the foot end of the mattress of the bed.

10 A further object of the invention is the provision of an attachment of the character described which can be quickly and easily adjusted to release the bed clothing when desired so that the bed clothing can be readily 15 removed from the bed and as readily replaced on the bed.

A further object of the invention is the provision of an attachment of the character described which will take up but little space, 20 will be inconspicuous and will not detract from the appearance of the bed, and which is thoroughly practical commercially.

Other objects and advantages of the invention will be apparent from the following description, considered in conjunction 25 with the accompanying drawings, in which—

Figure 1 is an elevation of the foot end of a bed equipped with an attachment embodying the invention,

30 Figure 2 is a slightly enlarged fragmentary vertical section through the foot end of the bed and through the attachment, the view being taken substantially along the line 2—2 of Figure 1, showing the attachment closed,

35 Figure 3 is a view similar to Figure 2, showing the attachment open and the bed clothing omitted,

40 Figure 4 is a fragmentary prospective view of the attachment alone in closed position.

In carrying out the invention, I provide a pair of cooperative clamping members or jaws A and B, respectively. The member 45 A preferably is a flat strip of metal or other suitable material bent edgewise substantially into U-shape to produce a web portion A¹ and a pair of parallel arms A². The member B also preferably is formed of a flat strip 50 of metal or other suitable material bent edgewise substantially into U-shape to produce a web portion B¹ and a pair of parallel arms B². The web portions A¹ and B¹ of the clamping members preferably are equal 55 in length and width and the effective length of the arms B² also preferably is equal to

the effective length of the arms A². However, the strip of material of which the member B is formed may be longer than the strip of metal of which the member A is formed so that the arms B² may include portions at 3 which are offset laterally of the remaining portions of the arms B² intermediate the length of the arms B², thus producing lateral pockets at 4 for a purpose 65 to be presently stated.

The extremities of corresponding arms A² and B² are hingedly connected by axially aligned pivot elements or pintles 5 so that the members A and B may swing relatively 70 to each other about the axial line of the pintles 5 to and from positions to contact flatwise with each other. Tension springs 6 are disposed in the pockets 4 between the arms A² of the member A and the laterally offset 75 portions 3 of the member B, one end of each of the springs 6 being attached, as at 7, to the associated offset portion 3 of the member B and the other end of that spring 6 being attached, as at 8, to the associated arm A² 80 of the member A. The springs 6 function to hold the device closed or in other words with the members A and B flatwise against each other. The members A and B may be opened 85 against the action of the springs 6 and may be maintained in opened positions through the agency of hooks 9 having shanks hingedly attached to the arms of one of the members of the device, as at 10 to the arms B², and being detachably engageable with screw 90 eyes 11 on the arms of the other member of the device, as the member A, the shanks of the hooks being sufficiently rigid and of sufficient length to maintain the web portions 95 of the members A and B apart a desirable 95 distance when the hook members 9 are engaged with the screw eyes 11.

From the foregoing description of the various parts of the device, the operation thereof may be readily understood. The arms B² 100 of the device are secured to the foot portion of a bed 12 so that the web portions of the members A and B will extend at right angles with the direction of length of the bed and will be substantially horizontal. Also, 105 the member B of the device is secured to the foot portion of the bed so that the upper edges of the web portions of the members A and B will be substantially level with the lower face of the members 13 of the bed 110 when the device is closed. When the device is attached to the bed 12 in the manner illus-

trated in Figures 1 to 3 inclusive, the lower end portions of the arms B² of the member B are secured by rivets 14 to the cross frame bar or rail 15 at the foot of the bed and the offset portions 3 of the arm of the member B and therefore the pockets 4 will be disposed above the cross member 15 of the bed frame. However, it is obvious that the arms B² of the member B of the device may be secured 10 to the foot end of the bed spring 16 on which a mattress 13 is supported by any suitable known fastening means (not shown), it only being essential that the device be secured to the foot portion of a bed so that the web 15 portions of the members of the device will be disposed below the plane of the upper surface of the mattress of the bed. The bed covering 17 is disposed on the mattress 13 so that the end portion of the bed covering at 20 the foot of the bed extends downwardly across the adjacent end of the mattress between the web portions of the members A and B. The members A and B and particularly the web portions thereof will be actuated by the springs 6 to firmly grip the portion of the bed clothing that is disposed between the members A and B and the bed covering thus will be securely held against accidental displacement from position to 25 cover the mattress at the foot of the bed. The web portions of the members A and B may be held apart by means of the hook members 9 and the screw eyes 11 against the action of the springs 6 when it is desired 30 to withdraw the end portion of the bed covering from position between the members A and B or when it is desired to insert portions of the bed covering between the web portions

of the members A and B. The device is simple in construction and effective and reliable in use. It makes possible the use of relatively short bed covering since no portion of the bed covering need be tucked underneath the mattress when the attachment is employed to prevent the bed covering 40 from being pulled accidentally on the mattress from position to cover the mattress at the foot end of the bed.

Obviously, the invention is susceptible of embodiment in forms other than that which is illustrated in the accompanying drawings, and I therefore consider as my own all such modifications and adaptations thereof as fairly fall within the scope of the appended 45 claim.

I claim:—

A clamp of the character described comprising a pair of substantially U-shaped members, corresponding arms of said members being hingedly connected, the arms of 60 one of said members having laterally offset portions, thus producing pockets, and tension springs disposed in said pockets and connecting the offset portions of the arms of 65 said one clamping member with the arms of the other clamping member, rigid hook members swingingly attached to the arms of one of said clamping members, and screw eyes carried by the arms of the other clamping member and adapted to be engaged by 70 said hook members, said hook members being of sufficient length to hold said clamping members in open position when said hook members are engaged with said screw eyes.

ALICE B. HOLT.
